FIG. 3

FIG. 2

1,120,084.

Patented Dec. 8, 1914.

APPLICATION FILED OCT. 8, 1913.

ANNUNCIATOR.

F. C. RIES.

UNITED STATES PATENT OFFICE.

FREDERICK C. RIES, OF MACON, GEORGIA.

ANNUNCIATOR.

1,120,084.

Specification of Letters Patent.

Patented Dec. 8, 1914.

Application filed October 8, 1913. Serial No. 794,150.

To all whom it may concern:

Be it known that I, FREDERICK C. RIES, a citizen of the United States, residing at Macon, in the county of Bibb and State of Georgia, have invented new and useful Improvements in Annunciators, of which the following is a specification.

This invention relates to annunciators such as are used in hotel offices to register guest calls and its objects are to provide a reliable annunciator of extremely simple and compact mechanical character; whereby the information concerning any particular call is furnished for a prolonged period after the call has been made and without confusion with any other calls which may have been made in the interim; and wherein the registering elements are automatically reset.

With the above objects in view the improved annunciator has a call registering element consisting essentially of a magnet and a resiliently pendant vibratory armature which is attracted to the magnet at the moment when the call is made and, when released is vibrant for several minutes. A number of these registering elements, corresponding to the respective guest rooms are mounted upon a board and are preferably employed in connection with an electric bell, light, or equivalent device operated when the call is made for the purpose of attracting the attention of the clerk.

An embodiment of the invention is illustrated in the accompanying drawing, in which:—

Figure 1 is a view illustrating diagrammatically an annunciator in which the features of the invention are incorporated. Fig. 2 is a view, partly in section, illustrating the detail construction of one of the registering elements. Fig. 3 is a horizontal sectional view on the line 3—3 of Fig. 2.

Similar characters of reference designate corresponding parts throughout the several views.

The annunciator comprises a board A, registering elements B, and preferably, as is usual, an electric bell C.

The invention resides essentially in the construction of the registering elements, each of which comprises a magnet 1, an armature 2, and a spring 3 supporting the armature. The armature 2 is preferably of cylindrical form and is secured to the spring 3 which, in the construction shown,

functions as a hanger and is in the form of a retractile coil, its upper end being secured, as by a pin 4, to the board A.

The spring 3 is positioned to aline the armature with the core 5 of the magnet and the insulating ring at the upper end of the magnet is fashioned to provide a recess 6 concentric to the core 5 and into which the armature is drawn when the magnet is energized. In this way the armature is positively held against lateral displacement, consequent to the vibrations of the bell, and when released, vibrates perpendicularly, its vibrations thus being more prolonged than would be the case if they had any lateral components. To facilitate accurate perpendicular vibrations of the armature it is attached to the spring 3 by means of an axially located knob 7 which fits in the lowermost constricted coil of said spring.

The number of registering devices corresponds to the number of guest rooms or call stations and in order that they may be distinguished each registering device is provided with a number or other identification symbol which may be conveniently provided on a band 8 encircling the magnet.

The circuits in which the magnets are arranged are, in the embodiment shown, assumed to be normally open, and are closed in the usual manner by the operation of a push button or switch in a guest room. When any particular guest registers a call by closing the circuit the electric bell rings to attract the attention of the clerk and the armature is drawn toward the magnet. When the latter is deenergized by the opening of the circuit and the magnet is released it vibrates for a period of several minutes. The seating of the armature on the core of the magnet and its subsequent vibrations both give notice of a call, and in this way, even though the attention of the clerk is not attracted when the bell rings, no difficulty is had in locating a call. If several of the magnets are vibrant in unison the sequence of the calls can be determined by noting the relative intensity of the vibrations. In Fig. 1 the registering device at the right side of the board is in normal condition and the other two are shown as in operation, their armatures being attracted toward the magnets. After the vibrations of an armature cease, the armature assumes its normal stationary position slightly above the upper

end of the magnet at which time the registering device is at rest and is reset for a further operation.

Having fully described my invention I
5 claim:—

In an annunciator a registering device comprising a magnet, a retractile coil spring above the magnet and an armature connected to the lower end of the spring and 10 suspended thereby in alinement with the core of the magnet, the armature being

formed as a cylindrical block and the magnet having a recess at its upper end concentric to its core.

In testimony whereof I have hereunto set 15
my hand in presence of two subscribing
witnesses.

FREDERICK C. RIES.
